UNITED STATES PATENT OFFICE.

FRANK DREW WINKLEY, OF MADISON, WISCONSIN, ASSIGNOR TO FULLER & JOHNSON MANUFACTURING CO., OF MADISON, WISCONSIN, A CORPORATION OF WISCONSIN.

CARBURETER.

1,014,988.

Specification of Letters Patent. Patented Jan. 16, 1912.

Application filed October 15, 1910. Serial No. 587,155.

To all whom it may concern:

Be it known that I, FRANK DREW WINKLEY, a citizen of the United States, residing at Madison, in the county of Madison 5 and State of Wisconsin, have invented certain new and useful Improvements in Carbureters, of which the following is a specification.

This invention relates in general to carbureters, and has among its principal objects to provide a carbureter which, when attached to a gas-engine, will be capable of supplying fuel to the combustion space of the engine in a thoroughly vaporized and 15 highly combustible condition for ready ignition.

It is well known that when the vapors from a liquid fuel enter a cold combustion chamber, such vapors are partially condensed, and under such conditions a liquid hydro-carbon engine, or, indeed, any liquid fuel engine is much more difficult to start than when the cylinders of the engine are heated to a certain degree which aids vaporization of the liquid fuel. Therefore, to effect the more perfect vaporization of the liquid fuel, in accordance with my present invention I interpose a removable heat-distributing member in the conducting passage 20 between the carbureter and the cylinder or combustion chamber of the engine at any suitable point, the heat-distributing member being so arranged within the passage that the oil or oil vapors passing through the 25 carbureter into the combustion chamber must necessarily come in contact with a heated wall or walls of such heat-distributing member. The heat-distributing member is made readily removable from the passage for the 30 purpose of heating the same by any suitable means; or its heating may be partially or wholly effected when in place.

The invention will be more specifically set forth and pointed out in the description embodied in this specification, and as shown 45 in detail in the drawings in which—

Figure 1 is a longitudinal section of my improved carbureter. Fig. 2 is a top plan view of Fig. 1. Fig. 3 is a side elevation 50 view of a slightly modified form, with parts broken away and other parts in section; and Fig. 4 is a view similar to Fig. 3, showing a further modification.

Referring to the drawings, and more particularly Figs. 1 and 2, the carbureter here-

in shown consists of a shell or casing 5 having an air-passage 6 running therethrough, at one end of which is located a throttle-valve 7 mounted upon a valve-stem 8 extending through one of the side walls of the 60 casing and into the body thereof. The casing is provided with an extension constituting in part the conductor leading from the carbureter to the combustion space of the engine, and in said conductor is formed a chamber 9, which may be of any desired form but is herein shown as circular in cross section. The conducting passage 6 in the carbureter opens into this chamber at one side thereof and leads from the opposite side 65 of the chamber through the coupling-nozzle 10.

The carbureter is provided with the usual feed-pipe or spray-tube 11 leading from a fuel receptacle (not shown) and having a conical discharge end 12 opening into the air passage 6. Coöoperating with the conical end 12 of the feed-pipe 11 is the needle valve 13, having a threaded connection with a boss 14 formed integral with the casing; said 70 needle valve having the usual thumb screw 15 for adjustment thereof.

With the exception of the chamber 9, the parts of the carbureter and conducting passage so far described are of an ordinary and well known type. The heat-distributing member coöperating with the chamber 9 consists in the several forms herein illustrated of a removable plug, the main body portion 16 of which is suitably cored to form connecting passages 17 and 18 on opposite sides of a central core 19, said passages merging into each other at opposite ends of the core, and the merged ends on one side 80 registering with the air passage 6, and on the other side with the coupling-nozzle 10. The plug is provided with a top portion 20 having a marginal flange 21 adapted to overlie and seal the upper edge 22 of the plug chamber 9 and effectively close the latter. 85 The heat-distributing member or plug is readily removable from the plug chamber by means of a handle 23, and any suitable means may be provided, if desired, for securing the plug within the chamber. The 90 nozzle 10 leading from the plug chamber is shown threaded for connection with any form of pipe leading to the cylinder or combustion space of the engine.

When the foregoing parts are suitably at- 110

tached to an engine to perform the purposes and functions for which they are intended, and it is desired to start said engine, giving it its initial explosion, the plug is removed from the chamber and suitably heated, whereupon it is then replaced in the chamber, and when the carbureted charge is drawn through the carbureter and passes through the passages 17 and 18 it comes in contact with the heated walls of the plug and thereby enters the combustion chamber in a thoroughly vaporized state ready for instant ignition and combustion.

In Fig. 3 a modified form of heat-distributing member is shown wherein the opposite side walls of the body of the plug are slightly cut away as shown at 24, and a passage 25 is formed in the cap portion 26 thereof, said passage 25 opening into the cut away portions 24 to form a connecting passage between the intake opening 27 of the plug joint 28 and the discharge opening 29. This modified form of heat-distributing member is also provided with a handle 30.

The heat-distributing member shown in Fig. 4 is of substantially the same construction as the heat-distributing member shown in Fig. 3, with the exception that its top is formed with a basin 31, into which a small amount of fuel of any character may be placed and ignited for the purpose of heating the plug without making it necessary to remove the same from the chamber, or for increasing or prolonging the heated condition of a previously heated plug.

I am aware that it is broadly old to preliminarily heat a carbureted charge by exhaust products from the engine passing through a jacket surrounding the conducting pipe from the carbureter.

My invention is distinguished from such a device in that it is designated chiefly to facilitate the starting operation of the engine and to neutralize the baneful effect of cold cylinder walls upon the initial charges received by the engine; the heat-distributing member of my invention being caused to absorb sufficient heat from some extraneous source to effect the heating up of the initial

charges when the engine is being started in operation.

I do not wish it to be understood that my invention is limited to the particular form of carbureter herein shown, nor to the particular forms of heat-distributing members disclosed, since it is obvious that the invention may be applied to any form of carbureter when used in connection with any form or type of engine using a liquid fuel and having one or more power cylinders.

Therefore, without confining myself to the particular details of structure herein shown and described, I claim:

1. In combination with a carbureter for gas-engines, a conductor leading from said carbureter to the combustion space of the engine and formed with a chamber intersecting the conducting passage, and a plug adapted to occupy said chamber and suitably cored to constitute a section of said conducting passage, said plug being removable to heat the same, substantially as described.

2. In combination with a carbureter for gas-engines, a conductor leading from said carbureter to the combustion space of the engine and formed with a chamber intersecting the conducting passage, and a plug adapted to occupy said chamber and suitably cored to constitute a section of said conducting passage, said plug having a flange adapted to overlie and seal the upper end of said chamber and being removable to heat the same, substantially as described.

3. In combination with a carbureter for gas-engines, a conductor leading from said carbureter to the combustion space of the engine and formed with a chamber intersecting the conducting passage, a plug adapted to occupy said chamber and suitably cored to constitute a section of said conducting passage, and a handle on said plug whereby the same may be readily removed and replaced, substantially as described.

FRANK DREW WINKLEY.
